3 Claims. (Cl. 229—62.5)

The invention relates to a bag, and in particular to a bag provided with an internal flexible filling tube which is closed off by the pressure of the filling material during the filling process, and which is attached to the bag in such manner that its outlet opening cannot be passed through its inlet opening.

In a known bag of this kind, the filling tube is attached through its entire length to the upper edge of the bag, and the two ends of the filling tube are in alignment with each other, and constitute the inlet and the outlet opening, respectively. The inlet opening lies in a part of the side edge of the bag adjacent to the upper edge.

The intention of this known construction is that the filling tube, when compressed by the rising filling material during the filling process, will be closed off in such manner that the bag may only be opened by making a hole in the side wall. Thus, as long as the wall of the bag is undamaged, one might be sure that no material has been removed from the filled bag. However, it has been found that this intention is not entirely realized in practice.

When using the known bag, it is indeed impossible for an unauthorized person to remove material from the bag by drawing the filling tube out of the bag through the inlet opening, for instance by means of a hook, removing material through the filling tube, and replacing the filling tube into its normal position within the bag. However, it has been found possible to open up the filling tube and its outlet opening, for instance by means of a stick, so that material may be removed through the filling tube.

It is the object of the invention to provide an improved bag, in which the above-mentioned disadvantage is eliminated.

Another object of the invention is to provide a bag constructed in such manner that it is entirely impossible for an unauthorized person to remove material from the bag without making a hole in the side wall.

A further object of the invention is to provide a simple and reliable method for producing a bag of the above-mentioned kind.

According to the invention, a tube closed at one of its ends is attached exclusively with its ends to one of the edges of the bag, and communicates through an opening in its side wall with the interior of the bag.

Whereas, in the known construction, the filling tube is connected through its entire length with the upper edge of the bag, so that the inlet opening, which is kept open by its connection with the side edge of the bag, the compressed filling tube, and the compressed outlet opening are in alignment with each other after the deformation of the filling tube by the filling material, the invention makes use of a tube of which the entire part between the ends is movable with respect to the wall of the bag. The part of this tube between the open end and the opening provided in the side wall constitutes the filling tube proper; the remaining part of the tube only serves to prevent the lateral outlet opening from being passed through the inlet opening.

Before the filling material is supplied to the bag, the part between the ends of the tube is spaced at some distance from the edge of the bag to which the ends are attached. During the filling process, the part between the ends of the tube is moved towards said edge, and pressed

2

against the same, whereby the tube is closed off. After that, the inlet opening, the compressed filling tube and the outlet opening are not in alignment with each other any more, nor can they be brought into alignment from the outside.

In a preferred embodiment of the invention, the tube has initially a V-shaped axis, and the opening the side wall is provided at about half the length of the tube.

In a suitable method for producing the bag according to the invention, a tube made of a thermoplastic material is folded along a line inclined with respect to the axis of the tube so as to obtain a V-shape, after which the tube is sealed at both ends to one of the edges of the bag, a separating foil being inserted in the tube at one of its ends during the sealing process.

In order to accelerate the production, the tube ends may be sealed to the edge of the bag in the same step wherein the said edge is closed.

The invention will be more fully explained by reference to the accompanying drawing, showing a preferred embodiment.

In the drawing:

FIG. 1 is a side view of the bag according to the invention wherein part of the front wall is broken away, and

FIG. 2 is a perspective view of the bag. The bag shown in the drawing has walls 1, which define a cavity. The walls preferably are made of a thermoplastic synthetic material. This material may be reinforced and may consist, for instance, of paper covered with a thermoplastic layer. Of course, other suitable materials may also be used for the bag.

A tube 2, preferably made of a thermoplastic synthetic material and closed at its end 3, is attached at both ends 3 and 4 to the upper edge 5 of the bag such that the tube 2 is supported in the cavity defined by the bag wall 1.

The tube 2 has been folded into a V-shape along a line 6, inclined with respect to the axis of the tube, and communicates with the interior of the bag through a lateral opening 7, substantially in the middle of the line 6. This opening is substantially horse-shoe-shaped on both sides of the line 6. The opening 7 has been shown at the underside of the tube. However, as an alternative, it would also be possible to provide the opening 7 at the upper side of the tube, likewise directly on the line 6.

The part 8 of the tube which is accessible through the open end 4, constitutes the filling tube proper. The remaining part 9 of the tube keeps the part 8 in such a position with respect to the upper edge 5 of the bag that the filling material exerts a lateral force on the part 8 during the filling process, whereby this part is pressed against the edge 5.

Since the distance between the closed end 3 of the tube and the outlet opening 7 is smaller than the distance between the ends 3 and 4, the portion 9 of tube 2 also prevents the opening 7 from being passed through the inlet opening 4, whereby material cannot be removed from the bag through the filling tube.

If both the bag wall 1 and the tube 2 are made of a thermoplastic material, the tube 2 may, after having been folded along the line 6, be sealed with its ends 3 and 4 to the upper edge 5 of the bag. Since the end 4, intended to operate as an inlet opening, must be kept open, a separating foil is inserted in the tube at this end. If the bag and the tube are made of polyvinyl chloride, the separating foil may consist of polyethylene. The tube 2 may be sealed to the edge 5 in the same sealing step wherein the edge 5 is closed.

The tube part 8 may be provided with a vacuum opening (not shown) through which a vacuum is generated in the bag during the filling process, in order to accelerate filling.

Although the invention has been described hereinabove by reference to a specific example, it is to be understood that the invention is not limited by this example, which may be altered and modified in various ways within the scope of the invention as set forth in the following claims. 5

I claim:

1. A bag comprising bag walls defining a cavity and at least one edge, and a flexible tube of V-shape in said cavity, said tube having opposite ends one of which is closed, said tube being attached to one of the edges of the bag, said tube being folded upon itself along a diagonal line intermediate the ends of said tube with an intermediate communication opening in said diagonal fold line. 10

2. A bag as claimed in claim 1 wherein said flexible tube has a fold line along which said tube is folded to confer the V-shape to the tube, said opening being in the vicinity of the fold line. 15

3. A bag as claimed in claim 2 wherein said bag walls and flexible tube are constituted of thermoplastic material.
